ALARM CLOCK ELECTRIC SWITCH

George W. Hall, Kansas City, Kans.

Application December 22, 1941, Serial No. 424,051

6 Claims. (Cl. 200—38)

This invention relates to an alarm clock electric switch and has for an object to provide a device of this character which may be manually set to open and close an electric circuit for turning off and turning on a radio, for example, to receive selected programs, or may be controlled by the setting of the alarm mechanism of the alarm clock to turn on an electrically operated device, such as a window opener or closer or a furnace when the alarm is energized.

A further object is to provide a device of this character which will be formed of a few simple, strong and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a front elevation of an alarm clock electric switch constructed in accordance with the invention.

Figure 2 is a rear elevation of the alarm clock electric switch.

Figure 3 is an end elevation of the alarm clock electric switch showing the outlets to receive plug in connectors.

Figure 4 is a top plan view of the alarm clock electric switch, with the casing in section.

Figure 5 is a fragmentary front elevation of the alarm clock switch, with parts in section, and showing the time selector mechanism controlled by the alarm clock winding shaft.

Figure 6 is a cross sectional view taken on the line 6—6 of Figure 5.

Figure 7 is a rear elevation of the alarm clock electric switch with the casing in section.

Figure 8 is a detail cross sectional view taken on the line 8—8 of Figure 1, showing the manual control lever of the time selector mechanism together with the indicators for indicating the position of the corresponding circuit closer whether in "on" or in "off" position.

Figure 9 is a detail cross sectional view taken on the line 9—9 of Figure 8, showing indicator.

Figure 10 is a front elevation of the indicator.

Figure 11 is a detail sectional view showing the alarm setting shaft extension.

Figure 12 is a detail sectional view taken on the line 12—12 of Figure 11.

Figure 13 is a side elevation of one of the time selector pins.

Figure 14 is a detail sectional view taken on the line 14—14 of Figure 7.

Referring now to the drawings in which like characters of reference designate similar parts in the various views, 10 designates a conventional

alarm clock which is disposed in an elongated casing 11 and the clock dial is exposed through a suitable opening in the front wall of the casing. The rear wall of the casing is hinged to one of the end walls as shown at 13 in Figure 4 and forms

15 a door which may be opened to afford access to the interior of the casing. The door is provided with louvers 14 through which the sound of the clock alarm may be heard. The alarm clock is located on one side of the center of the casing

20 and the adjacent end wall of the casing is equipped with outlets 15 for plug in connectors to turn on electric appliances of any type when the alarm mechanism of the clock is energized. Disposed on the opposite end wall of the casing

25 are outlets 16, similar to the outlets 15, adapted to receive plug in connectors to both turn on and turn off electric devices, such as a radio, at predetermined time intervals to receive selected programs. The time selector and its circuit

30 closer, controlled by the main spring winding shaft, is disposed on the same side of the center of the casing as the outlets 16 and will be first described, and then the mechanism controlled by the alarm winding shaft and its circuit closer will be described.

As best shown in Figures 1 and 4, the time selector mechanism includes a disk 17 exposed through a suitable opening 18 in the front wall of the casing, and a dial 19 disposed outside of

40 the disk and concentric therewith. The dial is graduated by numerals designating hour periods through twelve hours, and by indicia designating half hour periods. Other graduations may be used. The disk 17 is assembled as a unit with a disk 20 through the medium of bolts 21 and spacers 22 which space the disks apart, see Figure 4.

Both disks are mounted to rotate as a unit with a driven shaft 23 which has a reduced end en-

50 gaged through a central opening in the disk 20 and rigidly secured to the disk by a nut 24. The shaft is rotatably mounted in an opening in a

55 longitudinal wall 25 which rises from the bottom of the casing, see Figure 6, and a spacing sleeve 26 is disposed on the shaft between the disk 20 and

the wall. The shaft is driven by a gear train designated in general by the numeral 27, from the main spring winding shaft 28 of the alarm clock 10. The ratio of the gear train is such that the time selector disk 17 is driven at the same speed as the hour hand of the clock.

Pins 29 are engaged through registering openings in both disks and are provided between the disks with respective collars which engage the disks to limit endwise movement of the pins when selectively shoved in to project beyond the inner face of the inner disk 20 or when pulled out to dispose the ends of the pins substantially flush with the inner face of the disk 29. The pins are arranged in an annular series concentric with the axis of rotation of the disks and individual pins are disposed opposite respective hour designating numerals on the dial 19, and opposite respective half hour indicia.

Pins 31 are engaged through registering openings in both disks and are arranged in an annular series concentric with the axis of rotation with the disk, these pins being disposed inwardly of the pins 29 and opposite respective half and hour designation indicia on the dial 19. Likewise the pins 31 are provided with stop collars 32 between the disks.

The pins of both annular series are frictionally held in the rear disk 20, see Figure 5, by springs 9 housed in radial openings 8 and maintained under compression by screw plugs 7 in the outer ends of the openings.

As best shown in Figures 4, 5, and 6, a circuit closer 32 is mounted on the front face of the wall 25 approximately at the bottom of the inner disk 20 and comprises a housing 33, and a pair of spaced stationary blade switch contacts 34, of the type shown in Figure 14, adapted to be cross connected by a bridging contact 35 which extends transversely of, and is secured to, a switch operating arm 36. The arm 36 is slidably mounted in openings in the housing 33 and is limited in endwise sliding movement in both directions by stop pins 37 which are engaged through respective slots 38 in the arm. The outer end of the arm is equipped with a lever 39 which extends vertically upward and is pivoted between its ends on a pivot pin 40 secured to the wall 25, see Figure 4. The upper end of the lever is directed toward the rear disk 20 and is equipped with cam head 41 which extends between the annular concentric series of pins 29 and 31, see Figure 3.

When a pin of the inner series is pushed in it will impinge against the head 41 of the lever 39 as it arrives at a point about midway between the top and the bottom of the casing during counter-clockwise rotation of the time selector disks, and will swing the upper end of the lever outwardly to move the bridging contact 35 into circuit closing position with both fixed contacts 34 to turn on a radio set at a predetermined time.

A pin 29 of the outer annular series is set or pushed in at the same time the pin of the inner series is pushed in to turn off the radio set at a predetermined time. When the pin 29 arrives at the head 41 of the lever 39 it will swing the upper end of the lever inwardly to move the switch arm 36 outwardly and disconnect the bridging contact 35 from the fixed contacts 34 to open the radio circuit and turn off the program selected to be heard during the time period corresponding to the setting of the two pins as just described.

The arm 36 is moved quickly to open and to closed circuit position and for this purpose a lever 42 is pivotally connected at the lower end to the

arm within the housing 33, and extends upwardly to a point above the shaft 23, see Figure 5, and is equipped at the upper end with a weight 43. The lever is pivotally connected intermediate its ends to the wall 25 by a pivot pin 44. When the lever 42 passes a vertical position in either direction under impulse of the switch arm 36, the weight 43 will accelerate movement of the arm 36 to quickly dispose the bridging contact 35 in open or closed circuit position.

The switch arm 36 may be operated manually to move the bridging contact 35 to open or closed circuit position and for this purpose a lever 45, see Figures 1, 5, and 8, is pivotally mounted intermediate its ends on a pivot pin 46 which projects above the top of the wall 25 at the left end thereof. The lever extends through an opening 47 in the front wall of the casing 11. The lever is connected to one end of a link 48, the other end of the link being connected to a lever 49 which is pivoted intermediate its ends to the front face of the wall 25 by a pivot pin 50, see Figure 5. The lower end of the lever 49 is provided with an eye 51 which loosely received the weighted lever 42 below the weight 43. When the lever 45 is manually moved to the right or to the left the weighted lever 42 will be actuated to move the arm 36, correspondingly for controlling the position of the bridging contact 35.

For indicating the position of the circuit closer 32 an indicating slide 52, see Figures 1, 8, 9, and 10, is mounted to slide from right to left, and reverse, in the opening 47 in the front wall of the casing 11 and is slidably secured to the rear face of the front wall of the casing 11 by guide screws 53 engaged in the wall and having their heads overlapping the slide. The slide is provided centrally on the front face with a red target 54 and the ends of the front face are provided with white targets 55. The lever 45 projects through an opening 56 in the slide and moves the slide endwise when the lever is manually moved, or when the lever is moved by the weighted lever 42 through the medium of the link 48, to display the red target and one of the white targets through a sight opening 57 in the front wall of the casing, below respective legends "on" and "off" marked above the sight opening. The red target is the indicating target and when exposed below either legend the legend indicates the position of the circuit closer 32.

As best shown in Figure 7, a current supply cable 58 enters the casing 19. One wire 59 of the cable is trained around to the front side of the wall 25 and is connected to one of the stationary contacts 34 of the circuit closer 32. A wire 60, see Figure 5, is connected to the other stationary contact and is connected to the outlets 16. The other wire 61 of the cable is connected to the outlets. Thus when the circuit closer is "on" the plug in connectors 16 will be energized, and will be dead when the circuit closer is "off."

A sign 62, see Figure 1, is marked on the front wall of the casing on a level with the head 41 of the circuit closer operating lever 39. The sign indicates where the pins operate the circuit closer during their circular path of travel.

Alarm controlled mechanism and circuit closer

As best shown in Figures 4, 6, and 7, the alarm winding shaft 63 is provided with a cam 64. During rotation of the shaft while the alarm is being sounded the cam will impinge against the end of a link 65, best shown in Figure 7. The

link is slidably secured to the back of the clock by a screw 66 engaged through a slot 67 in the link. The link extends horizontally along the back of the wall 25 and is pivoted as shown at 68 to a lever 69 which is pivoted at its upper end to the back of the wall as shown at 70. The lower end of the lever is pivotally connected to a horizontally disposed operating arm 71, as shown at 72. The arm actuates a circuit closer 73 which will now be described.

The circuit closer 73 is mounted on the rear face of the wall 25 as best shown in Figure 6, opposite the circuit closer 32 of the time selector mechanism. The circuit closer comprises a housing 74, and a pair of spaced stationary blade switch contacts 75, of the type shown in Figure 14, adapted to be cross connected by a bridging contact 76 which extends transversely of, and is secured to, the operating arm 71. The operating arm is slidably mounted in openings in the housing 74 and is limited in endwise sliding movement in both directions by stop pins 77 which are engaged through respective slots 78 in the arm. When the arm 71 is pushed inward by the cam 64, link 65, and lever 69, it will move the bridging contact 76 into circuit closing position with both fixed contacts 75 to turn on an electric appliance such as a cooker, window opener or closer, furnace, or other appliance. The circuit closer 73 must be moved to open circuit position manually as will presently be described.

The arm 71 is moved quickly to open and to close the circuit closer 73 and for this purpose a lever 79, see Figure 4, is pivotally connected at the lower end to the arm outside of the housing 74, and extends upwardly to a point at about the level of the shaft 23, and is equipped at the upper end with a weight 80. The lever is pivotally connected intermediate its ends to the wall 25 by a pivot pin 81. When the lever 79 passes a vertical position in either direction, under impulse of the cam 64, or manual control devices about to be described, the weight 80 will accelerate movement of the arm 71 to quickly dispose the bridging contact 76 in open or closed circuit position.

The switch arm 71 may be operated manually to move the bridging contact 76 to open or closed circuit position and for this purpose a lever 82, see Figures 4, 5, and 7, is pivotally mounted intermediate its ends on a pivot pin 83 which projects above the top of the wall 25 at the center thereof. The lever extends through an opening in the front wall of the casing 11. The lever is connected to one end of a link 84, see Figure 7, the other end of the link being connected to a lever 85 which is pivoted intermediate its ends as shown at 86 to the rear face of the wall 25. The lower end of the lever 85 is provided with an eye 87 which loosely receives the weighted lever 79 below the weight 80. When the lever 82 is manually moved to the right or to the left the weighted lever 79 will be actuated to move the arm 71 correspondingly for controlling the position of the bridging contacts 76.

For indicating the position of the alarm operated circuit closer 73, an indicating slide 88, see Figure 7, is mounted to slide in an opening in the front wall of the casing 11 and is slidably secured to the rear face of the front wall by guide screws 89. Slide is provided centrally with a red target 90, and at the ends with white targets 91, see Figure 1, and the lever 82 projects through an opening in the slide to move the slide endwise. When the lever 82 moves the slide, or when the slide

is moved by the alarm operated lever 85, the red target and one of the white targets is displayed to a sight opening 92 in the front wall of the casing, below respective legends "on" and "off" marked above the sight opening, the red target being the indicating target, as heretofore described.

Referring again to Figure 7, there will be seen the current wire 59 is provided with a branch 10 93 which is connected to one of the stationary contacts 75 of the circuit closer 73. A wire 94 is connected to the other stationary contact and is connected to the outlets 15. The other wire 61 of the supply cable 58 is provided with a branch 95 which is connected to the outlets 15. Thus when the circuit closer 73 is "on" the plug in outlets will be energized, and will be dead when the circuit closer is "off."

Access to the interior of the casing is afforded 20 by releasing the catch 96 of the door 12 so that the alarm winding shaft 63, alarm setting shaft 97, see Figure 4, main spring winding shaft 28, may be accessible. The conventional silent and alarm button 98 is made accessible from the exterior of the casing through the medium of a button 99, see Figures 11 and 12, having a hollow stem 100 engaged through the top of the casing and threadably receiving the shaft 101 of a yoke 102 which embraces the stem button 98.

30 It will be pointed out that a substantially triangular bearing plate 103, see Figures 5, 6, and 7, is secured to the wall 25 and to the clock through the medium of bolts 104 and spacing sleeves 105. The plate is provided with openings to receive the main spring winding shaft 28, see Figure 4, the shaft 23 which actuates the time selector disk and the shaft 104 which supports the intermediate gear of the gear train.

Since the operation of the parts has been described as the description of the parts progressed it is thought that the invention will be understood without further explanation.

What is claimed is:

1. The combination with an alarm clock having a main spring winding shaft and an alarm winding shaft, of a time selector disk connected to the main spring winding shaft to be rotated by the shaft, concentric annular rows of push pins on the disk corresponding to time periods, a circuit closer, lever mechanism connected to the circuit closer and operated by the pins of one annular series to open the circuit closer and operated by the pins of the other annular series to close the circuit closer, a cam on the alarm winding shaft, a second circuit closer, lever mechanism connected to the second circuit closer and operated by the cam to close the second circuit closer, and manually operable means for opening the second circuit closer.

2. The combination with an alarm clock having a main spring winding shaft, of a time selector disk connected to the main spring winding shaft to be rotated by the shaft, concentric annular rows of push pins on the disk corresponding to time periods, a circuit closer, a lever connected to the circuit closer having the free end disposed between said rows of push pins and adapted to be engaged by a pushed in pin of one row to swing the lever to open the circuit closer and adapted to be engaged by a pushed in pin of the other row to swing the lever to close the circuit closer, a weighted lever pivoted intermediate its ends adjacent the first named lever and connected to the circuit closer to accelerate opening and closing of the circuit closer, means

connected to the weighted lever for manually moving the weighted lever to open and close the circuit closer, and means connected to the first named means adapted to indicate whether the circuit closer is in open or closed position.

3. The structure as of claim 2 and in which the first named means comprises a manually operable lever, a lever pivoted intermediate its ends and connected at one end to the manual lever, and an eye on the other end of the second named lever loosely receiving the weighted lever to swing the weighted lever when the manual lever is actuated.

4. The structure as of claim 2 and in which the last named means comprises a slide displaying a distinctively colored target, said slide having an opening, a manually operable lever engaged through said opening and connected to the weighted lever to be moved by the weighted lever to shift the slide, and indicia associated with the slide co-operating with the target.

5. The structure as of claim 2 and in which the circuit closer comprises, a pair of fixed switch contacts adapted to receive respective circuit

wires, a slidably mounted operating arm connected to both the push pin operated lever and the weighted lever, and a bridging switch contact extending transversely of the operating arm adapted to cross connect the fixed switch contacts.

6. The combination with an alarm clock having an alarm winding shaft, of an endwise sliding link, a cam on the shaft adapted to engage the link and move the link endwise, a lever pivoted at one end to swing in an arc and pivotally connected intermediate the ends to the link, a circuit closer connected to the free end of said lever, a weighted lever pivoted intermediate its ends adjacent the first named lever and connected to the circuit closer to accelerate opening and closing of the circuit closer, means connected to the weighted lever for manually moving the weighted lever to open and close the circuit closer, and means connected to the first named means adapted to indicate whether the circuit closer is in open or closed position.

GEORGE W. HALL.
